UNITED STATES PATENT OFFICE.

WADE S. GALVIN, OF AKRON, OHIO.

DESIGN FOR A TIRE TREAD.

Application filed May 8, 1926. Serial No. 17,615. Term of patent 14 years.

To all whom it may concern:

Be it known that I, WADE S. GALVIN, a citizen of the United States, residing at Akron, in the county of Summit and State of Ohio, have invented a new, original, and ornamental Design for Tire Threads, of which the following is a specification, reference being had to the accompanying drawings, forming a part thereof.

In the drawings:

Figure 1 is a top plan view of a portion of the tire tread; and

Figure 2 is a fragmentary cross-section on the line 2—2 of Figure 1.

I claim:

The ornamental design for a tire tread, as shown.

WADE S. GALVIN.
